BODY FOR A PIPE HANGER CLAMP

Henry J. Marik, Youngstown, Ohio, assignor to
Metelco, Inc., Struthers, Ohio

Filed Feb. 2, 1967, Ser. No. 5,667

Term of patent 14 years

(Cl. D54—1)

FIG. 1.

FIG. 2.

FIG. 3.

FIGURE 1 is a perspective view of a pipe hanger clamp, showing my new design,

FIGURE 2 is a longitudinal sectional view taken through the clamp shown in FIGURE 1, and

FIGURE 3 is a horizontal section corresponding to the line 3—3 of FIGURE 2.

The side opposite to that seen in FIGS. 1 and 2 is similar thereto in appearance.

The characteristic feature of my design resides in the converging line effect resulting from the multiplanar taper of the body flanges, as shown.

I claim:

The ornamental design for a pipe hanger clamp, substantially as shown and described.
